HERBERT T. HERR, OF PHILADELPHIA, PENNSYLVANIA, ASSIGNOR TO WESTINGHOUSE ELECTRIC & MANUFACTURING COMPANY, A CORPORATION OF PENNSYLVANIA.

BLEEDER TURBINE.

Application filed June 17, 1925. Serial No. 37,733.

My invention relates to fluid pressure turbines of the so-called bleeder type wherein steam or other fluid is extracted at various pressures for the purpose of feed water heating, process work, or for other uses.

In the accompanying drawings, Fig. 1 is a side view, in elevation, of a steam turbine constructed in accordance with one form of my invention; Fig. 2 is a transverse sectional view of the turbine shown in Fig. 1 on the line II—II thereof; Fig. 3 is a fragmentary longitudinally sectional view of the structure shown in Figs. 1 and 2, being taken, for example, on the line III—III of Fig. 2; Fig. 4 is a bottom view of the turbine shown in Fig. 1 with a portion of the cover plate broken away; Fig. 5 is a fragmentary sectional view similar to Fig. 2 and illustrating a modified form of my invention; Fig. 6 is a developed bottom view of a turbine casing constructed in accordance with the structure of Fig. 5; and Fig. 7 illustrates a modified form of fluid exit passage which may be used to advantage.

It is well-known to extract steam from a turbine at various pressures for the purposes of heating feed water in successive steps and for analogous uses, as fully set forth in U. S. patent to De Ferranti, No. 938,809, granted October 26, 1909. De Ferranti points out the thermo-dynamic advantage of a large number of extraction points, but serious mechanical difficulties are encountered when it is attempted to extract at a large number of points for the reason that the steam within a given turbine and at a given pressure is in the form of a relatively thin, annular band, as defined by the appropriate stage. In attempting to extract steam at two pressures relatively close to each other, it is necessary to tap the two corresponding bands or zones of fluid within the turbine, and difficulties are encountered in the way of mechanical clearances, etc., in supplying the proper passage members for the extraction of steam from the relatively narrow zones and for its transfer to conduits of the usual type.

In accordance with my invention, I cast or otherwise mount a plurality of ribs on the exterior of the turbine casing, preferably the bottom thereof, said ribs coacting to define a grid. I then provide relatively long, narrow slots opposite the appropriate steam

zones, one of said slots opening into each compartment of the grid. I then place a suitable cover member over the grid with openings therethrough into each of the compartments thus defined, attaching the extraction conduits in said openings.

Referring to the drawings for a more detailed understanding of my invention, I show a conventional turbine in Fig. 1, the particular machine illustrated being of the well-known impulse reaction type having an impulse section at 11, a reaction section at 12, the latter comprising upper and lower casing members 13 and 14 and further having an exhaust connection 15. The reaction section includes a plurality of annular rows of blades wherein the steam is successively expanded, thereby dividing the steam into a series of relatively thin isobaric annuli. Steam is admitted to the impulse section 11 through a suitable conduit 16 under the control of a valve 17.

It being desired to extract steam at, for example, ten points in the reaction section, I provide the under surface of the lower casing member 14 with a grid of integral ribs, as shown at 18—18 in Figs. 2, 3 and 4. Said ribs are preferably sufficiently high so that the outer edges thereof may be machined to a surface of rotation having a diameter at least equal to that of the bolting flange 19—19. Thus interference of the members 19 with the tool is avoided.

Within the casing 12 is a spindle indicated at 20 in Fig. 3 having the well-known moving blades 21—21 thereupon interleaved with suitable rows of fixed blades 22—22, all as is well known and understood in the art. Opposite or before appropriate moving rows 21—21, relatively long, narrow slots 23—23 are provided in the turbine casing, one of said slots opening into each of the grid compartments, as shown in Fig. 4. By making said slots relatively long and narrow, each extracts steam only from the steam zone of a given stage, thus permitting extraction at a large number of points with the assurance that appropriate pressure differences will be maintained between the respective slots, and without the necessity of unduly lengthening the whole turbine. Longitudinally adjacent slots are preferably disposed in staggered or offset relation forming two longitudinal rows of slots. This permits wider compart-

ments and sufficient space for ribs 18 of required strength.

A cover plate 24 is fitted over the grid members 18-18 and bolted in place so as to define a plurality of substantially closed compartments, and in this cover plate suitable pipe attaching means, such as flanges 25-25, are mounted so as to permit of the ready attachment of conduits 26-26 which may lead to suitable feed water heaters or other consuming devices.

Preferably, the extraction openings through the cover plate 24 are placed at substantially the lowest point in the associated compartment so that all condensation may drain away through the extraction conduits.

It will be noted that the longitudinal strength of the turbine casing would be seriously impaired by the series of slots 23-23 were it not for the fact that the ribs 18-18 add material strength to the structure, rendering the bridge members between adjacent slots of T cross-section, for example, whereby sufficient strength may readily be provided to meet the demands, and the turbine cylinder structure is further strengthened by the cover plates 24 suitably secured to the grid ribs.

Where it is desired to extract at even more points than indicated in the structure of Figs. 1 to 4, inclusive, the grid arrangement may be such as to define three longitudinal rows of compartments as indicated in Fig. 5, a developed view of the underside 35 of the turbine casing with its three rows of compartments and associated slots being shown in Fig. 6.

Under certain conditions, sufficient steam may be extracted through a row of small 40 holes 23' as indicated in Fig. 7 rather than through a long, narrow slot, under which conditions the structure of Fig. 7 is preferable, inasmuch as the strength of the casing is not as seriously affected thereby.

While I have shown my invention as applied only to the lower half of a turbine casing, it will be obvious that it may be applied as well to the upper half except for the inconvenience of opening up all the extraction 50 connections if it be desired to remove the cover of the casing for the inspection or repair of the spindle. By thus providing extraction openings both on the upper and lower halves of the casing, the number of 55 openings and the areas of the respective openings may be largely increased without increase in the length of the turbine. If desired, the cover alone may be provided with extraction openings, as where the turbine foundation or exhaust casing interferes with conduits beneath the casing.

While I have shown my invention in but two forms, it will be obvious to those skilled in the art that it is not so limited, but is 60 susceptible of various other changes and

modifications, without departing from the spirit thereof, and I desire, therefore, that only such limitations shall be placed thereupon as are imposed by the prior art or as are specifically set forth in the appended 70 claims.

What I claim is:

1. In a turbine having a casing member provided with a series of rows of fixed blading surrounding a spindle having a series 75 of rows of moving blading interleaving with said rows of fixed blading, respectively, bleeding slots in said casing opposite certain of said rows of moving blades and between successive rows of fixed blades, flanges on 80 the exterior of said casing surrounding each of said slots, respectively, cover means secured to and coacting with said flanges to define a plurality of closed chambers, and conduit means for conducting bled motive 85 fluid from each of said chambers, respectively.

2. In a turbine having a casing member provided with a series of rows of fixed blading surrounding a spindle having a series of rows of moving blading interleaving with said rows of fixed blading, respectively, relatively long narrow bleeding slots in 90 said casing opposite certain of said moving rows, respectively, longitudinally adjacent 95 slots being peripherally staggered with respect to each other, a grille work of integral flanges on the outer surface of said casing and surrounding each of said slots, respectively, cover means over said flanges, whereby a closed chamber is defined in association with each of said slots and having a width greater than the longitudinal spacing of 100 longitudinally adjacent slots, and conduit means for translating bled motive fluid from each of said chambers, respectively.

3. In a turbine, a split casing member of circular cross-section, the halves whereof are joined by bolting flanges, an exterior grid of integral flanges on one of said casing halves forming a plurality of compartments 110 therewith, said flanges having a height at least equal to the height of said bolting flanges, whereby the edges of said grid flanges may be machined to a surface of rotation, a peripheral bleeding slot opening into each compartment, respectively, cover means for said grid, and conduits tapping each closed compartment thus formed.

4. The combination with a turbine casing provided with a plurality of narrow adjacent peripheral bleeding slots therein, of integral reinforcing ribs on the bridges between adjacent slots and extending continuously around each of said slots, a cover member secured to said ribs and coacting therewith to define a plurality of closed chambers, and conduit means tapping each of said chambers for translating the motive fluid escaping thereinto.

5. In a bleeder turbine, blading means wherein the motive fluid is expanded through a series of relatively thin isobaric annuli, a casing having a series of adjacent, relatively long, narrow, peripheral bleeding slots therein, respectively disposed in radial alignment with certain of said annuli, integral reinforcing ribs on the bridges between adjacent slots and extending continuously around each of said slots, a cover

member secured to said ribs and coacting therewith to define a plurality of closed chambers, and conduit means tapping each of said chambers for translating the motive fluid escaping thereinto. 15

In testimony whereof, I have hereunto subscribed my name this eighth day of June, 1925.

HERBERT T. HERR.
